CLAIM

The ornamental design for an assay device with LCD display, as shown and described.

DESCRIPTION

FIG. 1 is a top front perspective view of an assay device with LCD display;

FIG. 2 is a front view of the assay device with LCD display;

FIG. 3 is a rear view of the assay device with LCD display;

FIG. 4 is a right side view of the assay device with LCD display;

FIG. 5 is a left side view of the assay device with LCD display;

FIG. 6 is a top view of the assay device with LCD display; and,

FIG. 7 is a bottom view of the assay device with LCD display.

The short dash lines in the drawings depict portions of the assay device with LCD display that form no part of the claimed design. The long dash lines in the drawings depict environmental subject matter and form no part of the claimed design.
